UNITED STATES PATENT OFFICE.

BERNARD NEUMARK, OF JOLIET, ILLINOIS.

CLOTHES-DIPPING APPARATUS FOR DYEING AND CLEANING.

Application filed November 5, 1927. Serial No. 231,267.

The present apparatus described herein and shown in the accompanying drawings is designed for dipping clothes in a bath for dyeing and cleaning purposes and one of the 5 important objects of the invention resides in the provision of means whereby the clothes may be lowered into the bath and raised therefrom in an easy and efficient manner.

Another very important object of the invention resides in the provision of means whereby the clothes when in the bath may be agitated with an oscillating movement.

Another very important object of the invention resides in the provision of a rack having a ring for supporting a plurality of clothes hangers and means for oscillating the ring about its axis.

With the above and numerous other objects in view as will appear as the description proceeds, the invention resides in certain novel features of construction, and in the combination and arrangement of parts as will be hereinafter more fully described and claimed.

In the drawing:

25 Figure 1 is a side elevation of the apparatus embodying the features of my invention showing the tub in vertical section,

Figure 2 is a top plan view thereof, with the handle 9^x omitted,

30 Figure 3 is an enlarged detail section taken substantially on the line 3—3 of Figure 2 looking in the direction of the arrow,

Figure 4 is a perspective view of the rack, Figure 5 is an enlarged detail sectional elevation showing the manner in which the main bracket is swivelly mounted,

Figure 6 is a detail section through a gear casing.

Referring to the drawing in detail it will 40 be seen that the numeral 5 denotes a tub, tank or other receptacle for receiving fluid such as dye or cleaning solution. A platform 6 is mounted adjacent the upper end of the tub 5 and may be of any preferred construction.

45 A substantially inverted L-shaped bracket 7 has its lower end swivelly mounted on a stationary member 8 suitably anchored on the platform 6 by means of a pin 9' or in any other suitable manner. At its free end the bracket 7 is preferably, though not necessarily, pro-

vided with a projection handle 9^x, Figure 1, for convenient swinging of the bracket 7 on said pin 9^x. A gear casing 9 is mounted on the lower end of the bracket 7 and has journaled thereon a shaft 10 with a worm gear on 55 the center thereof as is indicated at 11 meshing with a worm 12 on a shaft 13 journaled in the casing and extending therefrom, the outer end having fixed thereon a hand crank 14. On the ends of the shaft 10 exteriorly of the 60 casing 9 there are affixed drums 15 having the ends of cables 16 anchored thereto to be wound thereabout. These cables 16 are trained over pulleys 17 at the intermediate portion of the bracket 7 and pulleys 18 at the other extremity 65 thereof. The other extremity of the bracket 7 is in the form of a bearing 19 with a vertical bore through which is slidable and rotatable a standard 20. Adjacent the lower end 70 of the standard 20 there is a cross member 21 to the extremities of which the cables are anchored. As the description has thus far progressed it will be seen that the standard 20 may be raised by winding the cable 16 on the drums 15 and may be lowered by unwinding 75 the cables from these drums.

A circular head 23 is fixed on the lower end of the standard and a plurality of eye bolts 24 extend downwardly from the periphery of the head in circumferential spaced relation the eyes being at the lower ends thereof, said eyes receiving a ring 25 which is formed with a plurality of spaced notches 26 at the upper side thereof preferably an equal number between each pair of the bolts 24 as 80 is clearly illustrated in Figure 4.

This ring is adapted to receive the hooks 26 of ordinary clothes hangers 27 so that a plurality thereof may be supported therefrom in spaced relation so that the garments 90 will depend downwardly therefrom. A member 28 is rotatable on the head 23 at an off center point and has a threaded stud 29 projecting laterally therefrom. A connecting rod 30 has a reduced extension 31 at one end 95 with a sleeve 32 threaded thereon for threaded engagement with the stud 29 to provide quick detachable connecting means between the connecting rod 30 and the head 23. The prime mover 34 in the form of an electric 100

motor is mounted on the platform 6 and the armature shaft 35 thereof has a pinion 36 fixed thereon. A casing 37, Figures 1 and 3, has a vertical shaft 39 journaled therein and extending through the top thereof. Within the casing 37 on the shaft 39 there is fixed a worm gear 40 with which is meshed a worm 41 on a horizontal shaft 42 journaled in the casing and through one side thereof. On the outer end of the shaft 42 there is fixed a gear 43 meshing with the pinion 36. On the outer end of the shaft 39 there is fixed a gear 44. A bracket 45 rises from the base alongside of the casing 37 and has a pin 46 mounted therein and rising therefrom on which is rotatable a gear 47 meshing with the gear 44. An arm 48, Figures 1 and 3, is fixed to the gear 47 and is longitudinally slotted as at 49. A pin 50 projects from the other end of the connecting rod 30 into the slot 49. It will thus be seen that when the connecting rod 30 is connected to the head 23 as just described and the motor 34 is in operation the gear 47 will be rotated to reciprocate the connecting rod 30 and thereby oscillate the head 23 about its axis.

In using this device the connecting rod 30 is disconnected at 29, 32 from the head 23 so that the rack may be raised by winding the cable 16 on the drum 15. When the rack is in a raised position the clothes hangers 27 may be engaged on the ring 25. The rack may then be lowered so that the clothes will dip in the solution in the tank 5. The connecting rod 30 will then be engaged with the head at the connection 29—32. The motor 34 will be energized so as to oscillate the rack as previously indicated and this will cause the clothes to be properly saturated with the dyeing or cleaning fluid.

From the above detailed description it will be seen that the present embodiment of the apparatus is simple in its construction, has its parts compactly and conveniently arranged, and is thoroughly efficient and reliable in operation. The present embodiment of the invention, however, has been disclosed in detail merely by way of example since in actual practice it attains the features of advantage enumerated as desirable in the statement of the invention and the above description. It will be apparent that changes in the details of construction, in the combination and arrangement of parts may be resorted to without departing from the spirit or scope of the invention as hereinafter claimed or sacrificing any of its advantages.

Having thus described my invention, what I claim as new is:

1. In an apparatus of the class described, a bracket, a vertical standard slidable in the upper end of the bracket, a rack on the lower end of the standard, means whereby the standard may be raised and lowered, and

means whereby the standard and rack may be oscillated.

2. In an apparatus of the class described, a bracket, a vertical standard slidable in the upper end of the bracket, a rack on the lower end of the standard, means whereby the standard may be raised and lowered, and means whereby the standard and rack may be oscillated, the said means for oscillating being detachable from the rack. 75

3. In an apparatus of the class described, a clothes hanger supporting rack, and means for oscillating the rack, and means for raising the rack along the axis of oscillation.

4. In an apparatus of the class described, a bracket, pulleys on the bracket, a bearing at the upper portion of the bracket, a standard slidable and rotatable in the bracket, cables, pulleys on the bracket over which said cables are trained, means for anchoring the cables to the lower portion of the standard, a rack on the lower end of the standard, and drums on the bracket for winding and unwinding the cables to raise and lower the standard and rack, and means for oscillating the standard and rack. 80

5. In an apparatus of the class described, a bracket, pulleys on the bracket, a bearing at the upper portion of the bracket, a standard slidable and rotatable in the bracket, cables, 95 pulleys on the bracket over which said cables are trained, means for anchoring the cables to the lower portion of the standard, a rack on the lower end of the standard, drums on the bracket for winding and unwinding the cables to raise and lower the standard and rack, means for oscillating the standard and rack, a plurality of eye bolts extending from the head in circular arrangement with the eyes at the lower ends thereof, and a ring extending through the eyes. 100

6. In an apparatus of the class described, a clothes hanger supporting rack, means for oscillating the rack, and means for raising the rack along the axis of oscillation, said oscillating means being detachable from the rack. 110

In testimony whereof I affix my signature.
BERNARD NEUMARK.
